WIRE INSULATING APPARATUS

Christopher J. Krogel, Cranford, N. J., assignor
to Western Electric Company, Incorporated,
New York, N. Y., a corporation of New York

Application April 5, 1949, Serial No. 85,620

2 Claims. (Cl. 92—38)

1

This invention relates to pulp insulating machinery, and more particularly to a method and apparatus for applying a sheet of pulp to a plurality of wires to be insulated.

In the process of insulating a plurality of wires with paper pulp, one prevailing method is to embed the wires in a sheet of insulating pulp and then to cut the pulp into insulating ribbons in which the wires are centered, with the ribbons being wrapped around the wire in a subsequent step. Different varieties of pulp and gauges of wire require different widths of insulating ribbons for best results, and it is therefore necessary to be able to vary this width when needed.

It is accordingly an object of this invention to enable the width of the insulating ribbons provided by the above method to be varied quickly and accurately.

Applicant accomplishes his purpose in the preferred embodiment of the invention by using a Fourdrinier type pulp insulating machine in which a plurality of spaced parallel wires are enclosed within a sheet of insulating pulp carried by the Fourdrinier belt. A plurality of spaced nozzles in two rows furnish slicing jets of liquid to sever the pulp sheet into ribbons, with means being provided to simultaneously adjust the two rows relative to each other transversely of the belt so as to vary the width of the insulating strips of ribbon.

Other objects and advantages will be apparent from a consideration of the following detailed description taken in conjunction with the attached drawing in which:

Fig. 1 is a front elevational view of the invention;

Fig. 2 is a top plan view of the invention, taken partly along the line 2—2 of Fig. 1;

Fig. 3 is a cutaway plan view showing the two nozzle carrying members before any relative adjustment has been made.

With reference to the drawing, the apparatus shown is part of a conventional Fourdrinier type paper insulating machine. A sheet of insulating pulp 11 is carried by a moving wire mesh belt 12 which passes over suitable rollers. A plurality of parallel wires 13 to be insulated approach the moving sheet of pulp 12 while traveling in the same general direction as the sheet and at the same rate of speed, and are caused to enter the plane of the sheet, thereby becoming embedded in it. Located generally transversely to the line of movement of the belt 11 are a pair of parallel headers 14 and 15, each header being supplied with an equal number of spaced nozzles 16, which are correspondingly spaced to form a series of pairs of nozzles. The nozzles 16, which are supplied with water at approximately forty pounds pressure by means of hoses 17 and 18, direct slicing jets of water under pressure against the sheet of insulating pulp as the pulp passes be-

neath the headers, thus cutting the sheet into ribbons.

The headers 14 and 15 are slidably supported by brackets 20 and 21, which are rigidly fastened to a bar 22. The bar 22 in turn is supported by means of bolts 23 which slide in slots 24 of L-shaped bracket 25, thus allowing movement of the bar 22 transverse to the path of the wire mesh belt 12. The L-shaped bracket 25 is hinged at the joint 26 to a rigidly supported bracket 27. This hinged joint allows the entire mechanism to be pivoted about the hinge 26, and raised up out of the way to facilitate the initial stringing of the wires.

The two headers 14 and 15 can be adjusted in position together across the belt 12 by means of the knurled nut 28. The nut 28 is rigidly connected to a shaft 29 having a threaded portion to engage a corresponding threaded portion in the bracket 21. By turning the knurled nut 28, the bar 22 and the two headers 14 and 15 are caused to move in unison across the path of the wire belt.

The movement of the two headers 14 and 15 relative to each other is afforded by the knob 32, which acts through gears 33 and 34 to impart motion to the gear 35. Opposite sides of the gear 35 engage rack 36, mounted on header 14, and rack 37, mounted on header 15. Any turn given to the knob 32 causes the gear 35 to move racks 36 and 37 in opposite directions, and thereby cause headers 14 and 15 to move relative to each other in a direction generally perpendicular to the path of the advancing wires.

A scale 40 is provided to give a visual indication of the relative position of the two headers at any time. Means is provided as indicated at 41 for producing a vacuum or suction condition immediately below that part of the wire mesh belt 12 which is struck by the water coming from nozzles 16, for a purpose hereinafter explained.

The number of nozzles in each header is chosen with respect to the number of wires to be insulated so that there will be a wire to correspond to every other pair of nozzles. The nozzles are also spaced so that the distance between adjacent nozzles on the same header is the same as the distance between adjacent wires.

In operation, the knurled nut 28 is adjusted until a pair of nozzles, one on each header, is directly above a wire being fed along on the sheet of pulp. The knob 32 is then turned, simultaneously causing the two headers 14 and 15 to move oppositely to each other in a direction transverse to the path of the advancing wire, and is turned until the scale 40 indicates that the nozzles 16 are in a position corresponding to the width of ribbon desired. Since there is a wire for every other pair of nozzles instead of for every pair, the cutting action of the jets of water will form alternate strips of ribbon, one having a

wire embedded and centered in it, and the next being a waste strip, the latter corresponding to each pair of nozzles which do not have a wire passing by between their jets. This waste pulp passes into a chest (not shown) and is subsequently reclaimed and reused.

At this point, if it is found that the wires passing through are not exactly centered between two adjacent jets, that is, if the ribbon insulation is found to be wider on one side of the wires than on the other side, the knurled nut 28 may be turned sufficiently to bring the wires into exact centering relation with their respective pairs of jets.

The wires on passing from the apparatus as herein described have formed on them ribbons of insulating pulp which are uniform with respect to the various wires, and which have the same width on each side of each wire. The wires are then in a position to proceed to the next stage 10 of the insulating process.

By using two headers which are relatively movable with respect to each other, it is possible to vary with ease the width of the insulating ribbon on each wire to any desired width. If one header were to be used, it would not be feasible to vary the width of insulating ribbon, as the nozzles could not readily be adjusted in position relative to each other.

There is an ideal width of insulating ribbon corresponding to each wire gage, type of pulp used, and the degree of beating to which the pulp is subjected. Where it is desired to change the gage of wire running through the insulating machine, or where it is desired to change the degree of beating of the pulp, the invention as herein described provides an accurate and quick adjustment to provide the desired ribbon width.

If it becomes necessary to change the type of pulp being used during the course of the wire insulating process, it is essential that the width of the insulating ribbon be changed without delay or without interfering with the overall process since the pulp insulation of wires is essentially a continuous process. Applicant's invention is particularly effective in this case in providing an immediate adjustment in ribbon width to conform to the new type of pulp being used.

Since the relative movement of the two headers is accomplished by one motion, instead of by two independent motions, the operator can tell by looking at the scale on one of the headers exactly what ribbon width is being provided without having to move around the machine and look at the scale corresponding to the other header.

Means is provided for creating a vacuum or suction beneath the wire mesh belt in the vicinity where the jets from nozzles 16 impinge against the wire carrying insulating sheet of pulp. This is essential to the operation as a whole since it has been found from experience that after slicing through the insulating sheet, part of the water, instead of passing through the openings in the belt, tends to bounce back up from the wire meshing and strike the insulating ribbons. This has the effect of pitting and tearing the ribbon, and also turning it up at the edges, thus making the ribbon unsuitable for insulating use. In addition, the pulp which is torn from the insulation sheet and ribbons by the action of the water tends to collect around the nozzles and drops off in wads on the ribbon when a sufficient amount has accumulated. In view of these problems, applicant creates a vacuum or suction condition below the water impinging points so as to prevent 70

the splatter water and splatter pulp from interfering with the insulation process.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. In pulp insulating apparatus, the combination with a driven Fourdrinier type belt for carrying thereon a sheet of insulating pulp of a given width having a plurality of spaced parallel wires embedded in and moving with the sheet, of two hollow members each having a set of nozzles comparable in number and relative spacing to the number and relative spacing of the wires in the sheet of pulp and each member being adapted to receive a liquid under pressure for direction in jets through the nozzles to divide the sheet of pulp into ribbons, an element to support the hollow members for longitudinal movement relative to each other transversely of the belt, parallel racks mounted on the hollow members, and a rotatable pinion interconnecting the racks whereby the hollow members may be moved to cause their nozzles to direct their jets of liquid to known positions on their respective sides of their respective wires to divide the sheet of pulp into ribbons of variable widths for each wire.

2. In pulp insulating apparatus, the combination with a driven Fourdrinier type belt for carrying thereon a sheet of insulating pulp of a given width having a plurality of spaced parallel wires embedded in and moving with the sheet, of two hollow members each having a set of nozzles comparable in number and relative spacing to the number and relative spacing of the wires in the sheet of pulp and each member being adapted to receive a liquid under pressure for direction in jets through the nozzles to divide the sheet of pulp into ribbons, an element to support the hollow members for longitudinal movement relative to each other transversely of the belt, parallel racks mounted on the hollow members, and a rotatable pinion interconnecting the racks whereby the hollow members may be moved to cause their nozzles to direct their jets of liquid to known positions on their respective sides of their respective wires to divide the sheet of pulp into ribbons of variable widths for each wire.

3. In pulp insulating apparatus, the combination with a driven Fourdrinier type belt for carrying thereon a sheet of insulating pulp of a given width having a plurality of spaced parallel wires embedded in and moving with the sheet, of two hollow members each having a set of nozzles comparable in number and relative spacing to the number and relative spacing of the wires in the sheet of pulp and each member being adapted to receive a liquid under pressure for direction in jets through the nozzles to divide the sheet of pulp into ribbons, an element to support the hollow members for longitudinal movement relative to each other transversely of the belt, parallel racks mounted on the hollow members, and a rotatable pinion interconnecting the racks whereby the hollow members may be moved to cause their nozzles to direct their jets of liquid to known positions on their respective sides of their respective wires to divide the sheet of pulp into ribbons of variable widths for each wire, means to support the element for movement transversely of the belt, and means to move the element with the hollow members and their respective nozzles of each pair initially aligned with each other to align the pairs of nozzles with their respective wires whereby subsequent relative movement of the hollow members will position their nozzles like distances on opposite sides of their respective wires.
